UNITED STATES PATENT OFFICE.

CARL J. PATTERSON AND OLIVER J. KILBURN, OF JACKSON, MICHIGAN.

AUTOMOBILE-HEATER.

1,396,522.

Specification of Letters Patent.

Patented Nov. 8, 1921.

Application filed January 10, 1921. Serial No. 436,086.

To all whom it may concern:

Be it known that we, CARL J. PATTERSON and OLIVER J. KILBURN, citizens of the United States, residing at Jackson, in the county of Jackson and State of Michigan, have invented certain new and useful Improvements in Automobile-Heaters, of which the following is a specification.

This invention relates to exhaust heaters for automobiles, and has for its object a simple construction that can be clamped over the exhaust manifold and run into the body of the car simply by making a hole therethrough. The primary object of the invention is to provide a heater which is so simple in construction that it is within the reach of almost any car owner and at the same time effectively accomplishes the heating.

In the drawings,

20 Figure 1 is a side elevation of a Ford power unit showing the heater clamped in place.

Fig. 2 is a vertical longitudinal section of the heater.

25 Fig. 3 is a cross section of the same taken on the line 3—3 of Fig. 2.

a designates the usual Ford cylinder block; b the crankcase cover, and c the transmission. d indicates the carburetor; e the intake manifold, and f the exhaust manifold. x designates the so-called stove that is clamped to the manifold by the band z fitting onto the stud i. This stove has a flue y leading to the carburetor air intake to furnish warm air to the carburetor. The intake manifold and exhaust manifold are bolted to the cylinder block by yoke-like clamps g which are threaded onto the studs i. These manifold clamps are quite common construction in all types of automobile engines where the two manifolds are on the same side of the engine. Our heater comprises simply a hood of sheet metal which at its forward end is bent into inverted U-shape with one of the legs of the U considerably longer than the other (see Fig. 3). At the rear end the same sheet of metal is bent into tubular form to form the pipe j. The apron m or long leg of the U of the forward portion is recessed at

40 k and l for the purpose of straddling the threaded studs upon which the manifold clamps engage, as will appear from Fig. 1. These openings straddle the two center studs. The clamps, as appears from Fig. 1, are

55 adapted to engage the metal of this depend-

ing apron m on either side of the apertures k and l, and when the nuts are screwed down on the threaded studs, these clamps securely hold the apron to the clamp seats on the two manifolds, thereby securely holding the 60 heater to the two manifolds at four widely spaced points along the length of the heater. The other leg of the heater simply rests in free space between the manifold and the engine.

65 At the front of the U-like portion is a flaring opening n, which is here shown of the same piece of material as the body of the U portion, and which obviously could be made separate. This forms a funnel to catch the 70 air thrown from the fan and direct it into the heater. Around the U metal sheet at the top thereof above the apron m is secured an asbestos sheet h that acts as a heat insulator. This fastening is accomplished by riveting or spot-welding the metal sheet o over this asbestos sheet. The pipe j is adapted to project into the interior of the body at the junction of the dash and floor board, as indicated in Fig. 1, at one side and below the 80 coil box p.

75 One of the features of this heater is that a simple butterfly valve q is mounted in the extreme end of the pipe j where it acts both as a control for the air passing through the 85 tube and also by reason of being at the extreme end can be used as a deflector. For instance, the heated air can be directed toward the driver of the car or away, just as desired, by simply turning this deflecting 90 valve slightly.

Another important feature of this construction is that the U-like portion of the heater also fits over the ordinary stove x and hence the air drawn into the stove has traversed the entire length of the exhaust manifold. It is, therefore, much hotter and is possible to cut down the carburetor needle valve adjustment so as to make a material saving in "gas."

100 What we claim is:

An exhaust heater for automobiles, comprising an open front and open bottom hood formed of a single piece of metal bent into inverted U section with the long leg of the 105 U arranged to run down the outside of the manifold forming an apron with a free bottom edge into which are cut recesses for straddling the yoke clamp studs and permitting the yoke clamps of the manifold to en-

110

gage the bottom of the apron to hold the heater to the engine, the top of the hood including the other leg of the U being supported in free suspension above and on the 5 inside of the manifold by the yoke clamps engaging the said apron, a reinforcing sheet of metal secured over the hood at the top and part way down both sides; and a sheet of heat insulating material retained between

such reinforcing sheet and the hood, the 10 sheet of metal forming the hood continuing to the rear where it is curled into a tube to deliver the hot gases to the body of the car.

In testimony whereof we affix our signatures.

CARL J. PATTERSON.
OLIVER J. KILBURN.
